UNITED STATES PATENT OFFICE.

WILLIAM P. DUNHAM, OF NEW YORK, N. Y.

SMOKER'S PIPE.

1,266,563.

Specification of Letters Patent. Patented May 21, 1918.

Application filed April 26, 1917. Serial No. 164,600.

To all whom it may concern:

Be it known that I, WILLIAM P. DUNHAM, a citizen of the United States, residing in the city, county, and State of New York, have 5 invented certain new and useful Improvements in Smokers' Pipes, of which the following is a specification.

My invention relates to pipes for smokers' use and has for its object to provide an improved construction for a pipe whereby any 10 obstruction at the bottom of the bowl at its junction with the smoke passage may be easily, quickly and positively removed. A further but subsidiary object of the invention 15 is to provide a device, permanently associated with or carried by the pipe, which may be used in coöperation with the improved structural features of the pipe proper to secure the result specified.

One of the problems of the pipe user is to 20 prevent clogging or stoppage of the pipe bowl and bore or smoke passage, especially where the latter enters the former, thereby insuring that the pipe shall "draw" well, and 25 various constructions have been suggested to realize this ideal in greater or less degree. Others again have not attempted to prevent the difficulty but have directed their efforts to providing a way for effectively clearing 30 the pipe when obstruction has taken place.

My invention, herein to be described, belongs to the last class rather than to the first.

It is a matter of common experience with 35 pipe smokers that a pipe soon tends to clog at the bottom of the bowl at the point where the stem bore or smoke passage enters. The material which does the clogging is a mixture of tobacco and ash more or less saturated with saliva and nicotine, and takes the 40 form of a hard baked mass called "dottle." This dottle usually occupies the bottom of the pipe bowl at the point mentioned and extends up into the bore of the pipe for a 45 short distance, thereby becoming, so to speak, locked into place.

To remove this dottle the smoker thrusts 50 a pipe cleaner, wire, hat or hair pin, or similar device, down the smoke passage into the bowl. Even when these devices are at hand their use is disagreeable and dirty. More commonly, the smoker inserts a knife blade into the bowl and endeavors to push the dottle away with the knife point.

My invention does not contemplate preventing the formation of the dottle, but does provide for its quick and certain removal.

My invention will be better understood by referring to the accompanying drawings in which Figures 1 and 2 represent, respectively, a side elevation of and a longitudinal central section through a pipe having a preferred form of my invention combined therewith; Fig. 3 represents a section taken along the line 3—3 of Fig. 1; Figs. 4 and 5 represent views, similar respectively to Figs. 5 and 4, of a pipe provided with a modified form of my invention; and Fig. 6 represents a section taken along the line 6—6 of Fig. 4.

In the drawings, which show (referring particularly to Figs. 1 to 3) the application of my invention to a very usual form of briar pipe, 1 denotes the bowl of the pipe and 2 a short shank integrally united to the bowl and having a smoke passage or bore 3 opening into the bottom of the bowl at one side as at 4. The usual bit 5, of greater or less length, is fitted to the outer end of the stem.

The shank 2, on its bottom adjacent to the bowl, is preferably scooped out or recessed, as shown at 6. Preferably this recess is given the form of a transverse cylindrical segment. The recess also preferably does not extend to or open directly into the bore 3. From the top of the recess a short straight passage 7 connects with the end of bore 3 as it opens into the pipe bowl.

A metal sleeve 8 having an opening 9 is mounted upon the shank 2 adjacent to the bowl, being preferably fitted upon an inner bearing sleeve 8' having flanged ends, and is adapted to be rotated to bring the opening 9 either in or out of registry with the recess 6. The flanged bearing sleeve 8' must, of course, 95 itself have an opening in registry with the recess 6.

The sleeve 8, diametrically opposite opening 9, is provided with a thickened portion or rib 10 which is longitudinally drilled so as to serve as a carrier for a pin 11 provided with a head 12.

The pin 11 and metal sleeves 8 and 8' may be finished in any desired way, as, by plating, or may be of gold, silver, or other metal. 105 They may, therefore, be made to add to the finish and richness of the pipe as a whole.

In use, should a dottle form in the usual

way, the sleeve 8 is turned by finger and thumb until the opening 9 is in registry with the recess 6. The pin 11 is then withdrawn by the aid of head 12 and thrust up 5 through the passage 7 thereby dislodging the dottle and forcing it upwardly and away from the end of the smoke passage; or, if the bowl is substantially empty the dottle may be thrown out by inverting the bowl.

10 In the form of the invention shown in Figs. 4 to 6, the sleeve 8 is considerably shorter than the inner bearing sleeve 8'. The passage 7 is continued along the bottom of the stem as an open slot and the bearing 15 sleeve is also provided with a slot in registry therewith. The pin 11 has its outer end fixed in the sleeve 8 and passes through the slot in the bearing sleeve and into passage 7 where it normally lies in the position 20 shown in Fig. 4 with its inner end just inside the smoke passage adjacent to the bowl. Preferably this inner end is provided with a small ball tip.

By sliding sleeve 8 toward the bowl, the 25 pin 11 will be thrust upwardly through the passage 7 so as to push the dottle into the bowl in the same manner as has been previously described in the case of the pipe shown in Figs. 1 to 3. Pin 11, lying 30 permanently in the passage 7, serves as a "feather" to prevent the sleeve 8 from rotating upon its bearing sleeve.

Various changes in detail may be made 35 within the scope of the invention and of the claims which follow and will be obvious to those skilled in the art. Thus the sleeve 8, instead of being arranged rotatably, as shown, may be made to move axially so as to uncover the recess 6 when desired, the 40 opening 9 being omitted; the bearing sleeve 8' would, in such case, have to be made longer, of course, or other ways of opening or closing the recess 6 and passage 7 may be employed.

45 The recess 6 may be omitted altogether, if desired, letting the passage 7, in such case, extend clear through to the outer surface of the shank.

And, of course, any pin or slender stick 50 such as a match stick or the like, may be substituted for the pin 10.

The cleaning passage 7, being downwardly directed, serves also as a drainage well for the fluid saliva residues and the 55 like which usually collect in the bottom of the bowl. This residue may be removed altogether by moving the sleeve 8 so as to open the cleaning passage exteriorly and this removal may then be facilitated by 60 blowing into the upper end of the smoke passage while the open end of the bowl is closed by the palm of the hand.

The adaptation of my invention to other forms of pipes will be obvious to those 65 skilled in the art.

Having described my invention, I claim:

1. As a new article of manufacture, a smoker's pipe comprising a bowl and shank portion joined thereto, the latter having both the usual smoke passage and a cleaning passage leading upwardly to enter the smoke passage adjacent its opening into the bowl, said cleaning passage being directed so that a match stick entered therethrough will act to loosen the dottle and thrust it 75 into the bowl.

2. As a new article of manufacture, a smoker's pipe comprising a bowl and an integral shank portion, the latter having both the usual smoke passage and a cleaning 80 passage leading upwardly to enter the smoke passage adjacent its opening into the bowl, said cleaning passage being directed so that a match stick entered therethrough will act to loosen the dottle and thrust it 85 into the bowl.

3. As a new article of manufacture, a smoker's pipe comprising a bowl and shank portion joined thereto, said shank being provided with two independent passages 90 which open into the bowl at a common point, the outlet of one passage being at the outer end of the shank whereby a smoke passage is formed and the outlet of the other passage being at the bottom of the shank whereby 95 a cleaning passage is formed adapted to be entered by a match stick so as to loosen and thrust the dottle into the bowl.

4. As a new article of manufacture, a smoker's pipe comprising a bowl and shank portion joined thereto, said shank being 100 provided with two independent passages which open into the bowl at a common point, the outlet of one passage being at the outer end of the shank whereby a smoke 105 passage is formed, and the outlet of the other passage being at the bottom of the shank whereby a cleaning passage is formed adapted to be entered by a match stick so as to loosen and thrust the dottle into the 110 bowl, and a removable closure for the outer end of the cleaning passage.

5. As a new article of manufacture, a smoker's pipe comprising a bowl and shank portion joined thereto, said shank being 115 provided with two independent passages which open into the bowl at a common point, the outlet of one passage being at the outer end of the shank whereby a smoke passage is formed, and the outlet of the other 120 passage being at the bottom of the shank whereby a cleaning passage is formed adapted to be entered by a match stick so as to loosen and thrust the dottle into the bowl, and a slidably sleeve embracing the shank 125 and having an opening adapted to register with the outer end of the cleaning passage.

6. As a new article of manufacture, a smoker's pipe comprising a bowl and shank portion joined thereto, the latter having 130

both the usual smoke passage and a cleaning passage, both of said passages opening into the bowl at a common point and the cleaning passage also opening on the under 5 side of the shank and being so directed that a match stick entered into said cleaning passage will loosen the dottle and clear the end of the smoke passage.

7. As a new article of manufacture, a 10 smoker's pipe comprising a body portion provided with a recess for tobacco having a smoke passage leading therefrom and also having a cleaning passage opening exteriorly as to one end while its other end 15 opens into said smoke passage at a point adjacent its origin, the direction of the cleaning passage being such that a match stick inserted into the cleaning passage will loosen the dottle and thrust it upwardly into

the tobacco recess and forwardly away from 20 the end of the smoke passage.

8. In a pipe, a bowl, a shank joined thereto and having the usual smoke passage, said shank also having a recess on the lower side thereof adjacent the bowl and a cleaning 25 passage connecting said recess with the interior of the bowl at the point where entered by the smoke passage so that a match stick entered through the recess into the cleaning passage will loosen the dottle and 30 thrust it upwardly into the bowl and forwardly away from the smoke passage, and a sleeve slidably fitted upon said shank and provided with an opening adapted to register with said recess. 35

In testimony whereof I have hereunto set my hand.

WILLIAM P. DUNHAM.
